(57) **CLAIM**

The ornamental design for a display screen with animated graphic user interface, as shown and described.

DESCRIPTION

FIG. 1. is a front view of a display screen with animated graphic user interface showing a first image of our new design;

FIG. 2. is a front view showing a second image thereof;

FIG. 3. is a front view showing a third image thereof;

FIG. 4. is a front view showing a fourth image thereof;

FIG. 5. is an enlarged view of the first image, at part 5-5 and 5-5;

FIG. 6. is an enlarged view of the second image, at part 6-6 and 6-6;

FIG. 7. is an enlarged view of the third image, at part 7-7 and 7-7; and,

FIG. 8. is an enlarged view of the fourth image, at part 8-8 and 8-8.

The appearance of the animated images sequentially transitions from the first image through the fourth image. The process or period in which an image transitions to another forms no part of the claimed design.

The broken lines shown in FIGS. 1 to 8 represent unclaimed subject matter of the display screen with animated graphic user interface and form no part of the claimed design. The “dot-dash” broken lines shown in FIGS. 1 to 8 represent the boundary of the claimed subject matter and form no part of the claimed design.
